UNITED STATES PATENT OFFICE

ALBERT F. FIFIELD, OF ST. CATHARINES, ONTARIO, CANADA, ASSIGNOR TO THE AMERICAN FORK & HOE COMPANY, OF CLEVELAND, OHIO, A CORPORATION OF OHIO

RAIL ANCHOR

Application filed October 26, 1928. Serial No. 315,166.

My invention relates to rail anchors and relates particularly to improvements in that type of rail anchors adapted to be continuously secured to the rail base by the power 5 of its inherent resiliency alone.

Rail anchors of this general type have been made in one or more pieces and my present invention is applicable to both one piece and 2 piece anchors.

10 An object of my present invention is to provide an improved rail anchor having a highly efficient form of spring retaining means at one end of the anchor adapted to retain it on a rail base and at the opposite 15 end of the anchor an element of means adapted to abuttingly engage the tie in an efficient manner to anchor the rail thereto.

Another object of my invention is to provide an improved form of retained spring anchor for railroad rails.

Another object of my invention is to provide an anchor having a resilient reach bar adapted to be disposed below a rail base and to be longitudinally twisted in a very simple 25 manner while affixing the anchor to the rail base for the purpose of increasing the gripping power of the anchor on the rail base flanges.

Another object of my invention is to provide 30 a rail anchor of the above type which may be easily removed from the rail base after being securely affixed thereto.

Another object of my invention is to provide 35 an anchor generally of the above type, which may be affixed to and/or removed from a rail base very easily, by the use of tools ordinarily had by track men.

Another object of my invention is to provide 40 an efficient rail anchor which may be produced in quantities at a minimum of cost.

Another object of my invention is to provide 45 a rail anchor wherein the different parts may be expeditiously and inexpensively made, each having the most favorable properties of resiliency, malleability and rigidity to withstand and operate under the conditions prevailing in the practice.

Other objects of my invention and the invention 50 itself will become more apparent from the following description of my inven-

tion and in which description reference will be had to the accompanying drawings forming a part of this specification:

Referring to the drawings: Fig. 1 illustrates, in perspective, a view of 55 a rail anchor embodying my invention applied to a rail base, a fragmentary part of a rail being indicated in phantom; and an attaching tool therefor;

Fig. 2 shows a perspective view of a clamping shoe comprised in the said embodiment;

Fig. 3 is a side elevational view of a fragment of the clamping shoe and a hooked end 60 of the reach bar comprised in the said embodiment;

Fig. 4 is a perspective view of another form 65 of clamping shoe which may be alternately employed;

Figs. 5, 6, 7, and 8, respectively, are other 70 differing forms of clamping shoes interchangeably adaptable for use in connection with the hooked end of an anchor reach bar as illustrated in Fig. 1 in place of the clamping shoes of Figs. 2 and 3, illustrated in connection with the reach bar in Fig. 1.

Fig. 9 illustrates in perspective view, another embodiment of my invention.

Referring now first to the embodiment of my invention illustrated in Figs. 1, 2 and 3, at 1, I show a rail having a base 2, laterally extending base flanges 3 and 4 and an upstanding rail head supporting web 5. The rail base flanges 3 and 4 terminate in vertical side edges, one of which is shown at 6, reference being had to Fig. 9, for the other vertical edge 6', Fig. 9, showing also a like rail base structure.

In Fig. 1, the fragment of the rail illustrated is merely indicated by dotted lines in order to show its position when gripped by the anchor which is shown in solid lines. The anchor comprises two parts, a resilient reach bar 7 and a clamping shoe 8, the clamping shoe being carried in a hooked end 9 of the reach bar and comprising an upper jaw 10 and a lower jaw 11. The jaws 10 and 11 are, as illustrated, adapted to embracingly engage the top and bottom surfaces of the rail base flange 4. The jaw 10 comprises an upwardly inclined jaw surface 12, while the

5 jaw 11 preferably comprises a flat upper surface of relatively large area and carries a depending railway tie engaging flange 28 adapted to butt a rail supporting tie to prevent longitudinal movement of the rail to which the anchor is attached, relative to the tie.

10 The reach bar 7 is adapted to underlie the rail base, as indicated, and terminates at the opposite side of the rail base in an upturned arm 15 which is bent at 16 to provide a down-turned pendant leg 17, the pendant leg 17 being deflected inwardly to permit its lower end surface 18 which is thus inwardly upwardly inclined relative to the rail base to engage with the top lateral corner 19 of the rail base flange 3.

15 In the normal form of the reach bar 7, the bottom end of the leg 17 would project below the level of the rail flange corner 19, but in applying the anchor to the rail, a tool 20 is projected through the opening 21 provided between the arm 15 and the leg 17 and the tip 22 of the bar is made to engage with the top 25 surface of the rail flange 3 in a portion near the rail web 5 and the tool 20 is then used as a lever pry, a lifting effort being given the handle end 23 of the tool and which is effective to lift the foot surface 18 of the leg 17, so that 30 its inner edge 24 is sprung inwardly over the corner 19 of the rail base flange 3, because of the inherent resiliency of the material of which the bar 7 is made, restoring the bar to a less stressed form. The foot 18 will press 35 downwardly with considerable power on the edge 19 in the effort of the bar to regain a more nearly unstressed form and the bar 7 being held rigidly by the jaws 10 and 11 of the shoe 8 to the rail base, prevents rotational 40 movement of the hooked end 9 of the bar so that the twisting effort imparted by the lifting of the inverted U-shaped portion of the bar, comprising the elements 15, 16 and 17, laterally of the arm 15, produces a torsional 45 grip on the intermediate portion 25 of the bar which underlies the rail base, and so long as the rail anchor comprising the bar 7 is left so attached on the rail base, the intermediate portion 25 will continue to be distorted torsionally, and reacting resiliently in the effort 50 to regain its normal form and exert a gripping effort on the rail base flange.

55 Referring now to Figs. 1 to 3, inclusive, of the drawings, the form of the connection between the hook 9 of the reach bar and the clamping shoe 8 will be well understood. As illustrated in Fig. 2, the clamping shoe 8 comprises an abutment flange 28 depending below the flat jaw surface 11 which is adapted 60 to engage intimately with the bottom surface of the rail base.

65 The upper jaw 10 projects upwardly from the flange 28 and is provided with an inclined jaw face 12 co-operating with the jaw face 11 to tightly and rigidly receive the flange

4 of the rail base. A lateral extension 13 of the jaw 10 and flange 28 is provided with an enlarged end 29. The enlarged end 29 and the portion 30 of the shoe provide shoulders 31 and 32, respectively, between which the hook 9 of the reach bar, Fig. 1, may be received. The rear surface 13, as illustrated in Fig. 2, is parti-cylindrical in form, conforming with the inner surface of the hook engageable therewith, whereas for the full width of the shoe comprising the width of the re-enforcing jaw portion 10, the enlarged end 29 and the intermediate portions 30 and 13, the groove 33 formed between opposing jaw surfaces 11 and 12 is extended and provide side jaw surfaces 11 and 12 to embrace the rail base. As indicated by the dotted lines at 34, the hook 9 is joined to the intermediate portion 25 of the reach bar which extends from the hook 9 below the rounded intermediate portion 13 of the shoe and below the jaw 11, as shown in Fig. 3.

70 The dotted lines in Fig. 2 indicate the form of the jaws for their full width. The portion 13 of the shoe is made rounded so as to form 75 a good tight fitting bearing for the hook 9 of the reach bar which may then rotate vertically about this bearing, as when placing the anchor on the rail.

75 The modus operandi of the anchor will now be understood. The tie abutting flange 28 of the clamping shoe 8 engages by its outer lateral surface with the lateral surface of a tie and longitudinal movement of the rail will effect a thrust pressure effort against the tie 100 by the surface of the flange 28 disposed below the rail.

80 The hooked end 9 of the reach bar carrying the clamp, will by virtue of this pressure, be slewed slightly around the other end 15, 105 to effect a wedging gripping of the rail base between the opposite jaws on the two ends of the reach bar, comprising at one end the jaws formed by the upper surface of the reach bar 7, and the end surface 18 of the 110 resilient loop leg 17, and at the other end the jaws 10-11 of the clamping shoe 8.

85 Due to the power of the distorted resilient loop 15, 16, 17, the anchor is held to the rail base flange, while the slewing accomplishes 115 an effective gripping of the rail base by its lateral flange edges.

90 The resilient retaining loops is of a most efficient form for the purpose, and is not loosed from the rail by the slewing of the 120 anchor in use.

95 Referring now to Fig. 4, a somewhat simpler form of clamping shoe is shown therein having jaws 10' and 11' with jaw surfaces formed like that of the foregoing embodiment by having the laterally extending portion 13' of the same cross-sectional area and form, no enlarged end, such as that shown at 29 in Fig. 2, being provided, this form otherwise being like that of the foregoing 130

embodiment and will help to explain the common features to the two embodiments.

In Fig. 5, another form of shoe is illustrated wherein from the jaw 11^a, depending loops 35 and 36 extend, being integrally joined to the sides by arms 37 and 38, respectively, and having parallel arms 39 and 40, respectively, integrally joined throughout their entire length with the tie abutting flange 28^a. In this way rectangular apertures 41 and 42 are provided through which the reach bar 7 may be projected and preferably will be projected therethrough before forming of the one or the other deflected ends of the bar so that in such a case, the shoe will be non-removably secured to the bar which will fit snugly in such a case within the apertures 41 and 42. Either end of the bar may be preformed, leaving the other end straight for insertion through the apertures, the straight end being then subsequently formed to the desired shape by giving it the form of the hook 9 or the form of the inverted loop 15, 16, 17, as the case may be. A pair of laterally disposed stiffening flanges 42 and 43 are provided on either side of the accurately formed outer surface of the shoe portion 13^a. The hook 9 of the reach bar is then forced over the portion 13^a of the shoe, so that the shoe and reach bar may then be handled and applied to the rail as a unitary rail anchor.

Fig. 6 possesses features common to the foregoing embodiments and is a clamping shoe having jaws similarly formed as in the foregoing embodiments, a depending rail tie abutting flange 28^b, as in Figs. 1 to 4, inclusive, laterally disposed flanges 42^b and 43^b for the reach bar hook, as in Fig. 5, and in addition the top and bottom surfaces of the jaws 10 and 11 are medially grooved as shown at 44 and 45 to snugly receive the reach bar forced into tight embracing engagement therewith to prevent relative lateral displacement of the bar and shoe as do the shoulders 29 and 30 on either side of the portion 13 of Fig. 2, and as is accomplished in Fig. 5 by the parallel arms 37-38 and 39-40.

Fig. 7 illustrates a simple form of shoe which may be made of sheet steel and comprises a single sheet of metal having a depending flange 28^c for engagement with a railway tie and a rail flange embracing arcuate extension 10^c, the intermediate portion 11^c adapted to engage with the under side of the rail flange. The shoe of Fig. 7 is adapted to be employed in the same manner as the shoe of Fig. 6 in combination with a reach bar of the same form as illustrated in Figs. 1 and 3, the hooked end of which would be suitably formed to enfold the portion 10^c of the shoe.

Fig. 8 illustrates a shoe for the reach bar as previously described, indicated in Fig. 8 at 7^c, which is like that illustrated in Fig. 7

except that from the depending flange 28^d, which corresponds to the flange 28^c of Fig. 7, an extension 46 extends upwardly to engage the inner surface of a downturned lip 47 of the jaw portion 11^d. The reach bar 7^c extends through the passage 48 provided by the three walls 11^d, 28^d, and 46 of the shoe and is prevented from lateral movement relative to the shoe by the engagement of corners of the reach bar 7^c with the inner walls of the passage as in Fig. 1. The hook 9 of the reach bar embraces the C-shaped shoe tongue 10^d.

Fig. 9 illustrates a rail anchor of the general type illustrated in the foregoing figures but wherein the reach bar 7^e terminates at its hooked end in a hook 9^e of such a size and having a tongue 90 disposed at such an angle as to directly engage by jaw portions 91 and 92, the top and bottom surfaces of the rail base flange 3 adjacent its vertical edge 6', with which the laterally adjacent portion 94 of the hook is engageable. The edges of the flange 3 engage the hook 94 adjacent the curved portion. The anchor of Fig. 9 terminates at its other end in an upstanding laterally extending inverted loop like that of the loop 15 of Fig. 1 and having its free end inwardly deflected for resilient pressure engagement with the upper corner of the rail base edge in a manner like that of the first embodiment, previously described herein. This anchor is secured to the rail base in the same manner as that illustrated in Fig. 1 as before described, and prevented from lateral movement by engagement of the lateral surface of the reach bar 7^e engaging with a railway tie with which it is placed in abutting relation.

This form of anchor is illustrated as being within the purview of my invention broadly considered, although I prefer forms having greater tie engaging surfaces disposed relatively lower than the tie-engaging surfaces of the embodiment of Fig. 9.

Having thus described my invention in a number of embodiments, I am aware that numerous and extensive departures may be made from the embodiments herein illustrated and described but without departing from the spirit of my invention.

I claim:

1. In a two-piece rail anchor, the combination with a bar having a hooked end and a retaining shoulder at its other end, said retaining shoulder adapted for engagement with the lateral edge of a rail base flange, a jaw element adapted to be fixed to the opposite rail base flange and interposed between said opposite rail base flange and said hooked portion of said bar, said shoe having a portion extending below the rail base and between said rail base and said intermediate bar portion, and a portion pendant therefrom and engageable with a relatively fixed abutment for the railway, said pendant portion

having portions embracing the lateral surfaces of said bar, said shoe carried on said bar as a unit therewith.

2. In a rail anchor, a reach bar having an intermediate portion adapted to underlie a rail base and terminating at one end in a reversely turned upstanding hook and at its other end in an upstanding laterally extending inverted loop, said hook adapted to encompass a rail base flange, the pendant end of the loop being normally inwardly deflected, said loop adapted for a lifting distortional movement to effect engagement by the free end of the pendant arm with an upper surface portion of the associated rail base flange.

3. In a rail anchor, a reach bar having an intermediate portion adapted to underlie a rail base and terminating at one end in a reversely turned upstanding hook and at its other end in an upstanding laterally extending inverted loop, said hook adapted to encompass a rail base flange, the pendant end of the loop being normally inwardly deflected, said loop adapted for a lifting distortional movement to effect engagement by the free end of the pendant arm with an upper surface portion of the associated rail base flange, and a shoe gripped between inwardly disposed surfaces of said hook and the associated base flange having a pendant tie engaging portion projecting exteriorly of the hook.

4. In a rail anchor, a reach bar having an intermediate portion adapted to underlie a rail base and terminating at one end in a reversely turned upstanding hook and at its other end in an upstanding laterally extending inverted loop, said hook adapted to encompass a rail base flange, the pendant end of the loop being normally inwardly deflected, said loop adapted for a lifting distortional movement to effect engagement by the free end of the pendant arm with an upper surface portion of the associated rail base flange, and a shoe gripped between inwardly disposed surfaces of said hook and the associated base flange having a pendant tie engaging portion projecting exteriorly of the hook, said shoe being grooved exteriorly to receive the hooked end of the bar, the grooved portion providing shoulders engageable with lateral surfaces of the bar to restrain the shoe and bar from relative lateral movements.

5. In a rail anchor, a reach bar having an intermediate portion adapted to underlie a rail base and terminating at one end in a reversely turned upstanding hook and at its other end in an upstanding laterally extending inverted loop, said hook adapted to encompass a rail base flange, the pendant end of the loop being normally inwardly deflected, said loop adapted for a lifting distortional movement to effect engagement by the free end of the pendant arm with an upper surface portion of the associated rail base flange, and a shoe gripped between inwardly

disposed surfaces of said hook and the associated base flange having a pendant tie engaging portion projecting exteriorly of the hook, said shoe provided with rail base flange gripping jaws, said jaws being of substantially greater width than the width of said hook. 70

In testimony whereof I hereunto affix my signature this 24th day of October, 1928.

ALBERT F. FIFIELD.
